UNITED STATES PATENT OFFICE

156,617

COMBINED BILLFOLD, COIN PURSE, KEY-CASE, AND LIPSTICK HOLDER

Henry R. Godfrey, Gardner, Mass.

Application March 21, 1949, Serial No. 1,510

Term of patent 14 years

(Cl. D87—3)

To all whom it may concern:

Be it known that I, Henry R. Godfrey, a citizen of the United States, residing at Gardner, in the county of Worcester and State of Massachusetts, have invented a new, original, and ornamental, Design for a Combined Billfold, Coin Purse, Key Case, and Lipstick Holder, of which the following is a specification, reference being had to the accompanying drawing, forming part thereof.

Fig. 1 is a plan view of the inside of a combined billfold, coin purse, key case, and lipstick holder embodying my new design;

Fig. 2 is a side elevational view thereof in an open position;

Fig. 3 is a rear elevation of the combined article in closed position; and

Fig. 4 is a side elevational view thereof in closed position.

I claim:

The ornamental design for a combined billfold, coin purse, key case, and lipstick holder, as shown.

HENRY R. GODFREY.
